UNITED STATES PATENT OFFICE

107,281

DESIGN FOR AN OUTDOOR WEATHERPROOF FEEDER

Harold R. Ray, Woodstock, Ill.

Application July 14, 1937, Serial No. 70,438

Term of patent 7 years

To all whom it may concern:

Be it known that I, Harold R. Ray, a citizen of the United States, residing at Woodstock, in the county of McHenry and State of Illinois, have invented a new, original, and ornamental Design for Outdoor Weatherproof Feeders, of which the following is a specification, reference being had to the accompanying drawing, forming a part thereof.

In the drawing:

Fig. 1 is a front perspective view of an outdoor weatherproof feeder showing my new design;

Fig. 2 is a cross sectional view thereof taken on the lines 2—2 of Fig. 1, and

Fig. 3 is a front elevational view of the same.

I claim:

The ornamental design for an outdoor weatherproof feeder as shown.

HAROLD R. RAY.
